METHOD OF BURNING LIQUID FUEL

Filed Feb. 15, 1926

UNITED STATES PATENT OFFICE

ALBERT L. KLEES, OF NEW YORK, N. Y., ASSIGNOR TO COMBUSTION UTILITIES CORPORATION, OF NEW YORK, N. Y., A CORPORATION OF MAINE

METHOD OF BURNING LIQUID FUEL

Application filed February 15, 1926. Serial No. 88,196.

The present invention relates to the combustion of liquid fuels and more particularly to improvements in the operation of burners for gas and oil fired domestic heating furnaces.

The combustion of oil or other liquid fuel is ordinarily accomplished in domestic heating furnaces by atomizing a jet of the oil with air or steam under pressure in the combustion chamber of a furnace through a small orifice nozzle, and igniting the air- or steam-oil mixture by contacting it with the flame from a gas pilot light or other source of heat as it leaves the tip of the nozzle. It has been proposed to operate furnaces for heating houses or the like with gas as the normal load fuel and to supplement the gas with oil during periods in which the demand for heat is greater than can be readily taken care of by the gas available. According to this proposed system the air-oil mixture issuing from the atomizing nozzle is ignited and rapidly vaporized by heat supplied from the flame of a gas burner of relatively much greater heating power than that furnished by the ordinary pilot light. Accordingly with a combination gas and oil burner such as that suggested it is possible to burn a relatively much cheaper grade of oil than can be used in the ordinary type of burner, burning oil only. It has been found, however, that the combustion of oil in a furnace either equipped with the common type of oil burner or with a gas-oil burner such as that suggested is generally accompanied by a flickering flame and a roaring noise of varying intensity which is very objectionable and disturbing to the householder.

The primary object of the present invention is to provide an improved method for effecting the combustion of oil in house heating furnaces without any objectionable combustion noise.

A further object of the invention is to provide a method of burning oil in house heating furnaces with a smoother and more efficient flame than that commonly produced with the ordinary type of oil or oil-gas burner above referred to.

With these and other objects in view the

invention consists in the improved method of burning liquid fuels hereinafter described and particularly defined in the claims.

The various features of the invention are illustrated in the accompanying drawings, in

Fig. 1 is a view in elevation, partly in section, of a standard type of domestic heating furnace equipped with an improved gas-oil burner apparatus suitable for burning oil in accordance with the method embodying the preferred form of the present invention.

Fig. 2 is a vertical section of the oil atomizing nozzle illustrated in Fig. 1; and

Fig. 3 is a plan view with parts cut away showing the relative arrangement of the gas burner and oil atomizing nozzle, taken on line 3-3 of Fig. 1.

The basic principle underlying the present invention has been evolved as the result of a large number of experiments carried out to determine the source of the considerable amount of noise produced when an air-oil mixture is injected under pressure into the combustion chamber of a house heating furnace and is ignited as it leaves the tip of the atomizing nozzle. It has been determined by these experiments that the roaring noise set up by the combustion of oil according to the methods now commonly employed in the burners of house heating furnaces results in great part from the practice of attempting to ignite the atomized air-oil mixture entering the combustion chamber at a time when the velocity of the jet issuing from the nozzle is greater (or sometimes less) than the rate of flame propagation of the atomized air-oil mixture.

Accordingly one feature of the present invention contemplates a new design of gas-oil burner having the gas burner so arranged relative to the oil atomizing nozzle that the ignition of the atomized oil-air mixture entering the combustion chamber will be effected by the gas flame at the instant that the velocity of the jet issuing from the tip of the atomizing nozzle substantially equals the rate of flame propagation of the mixture.

In the drawings 10 indicates a standard type of coal burning domestic heating fur-

nace equipped with a combination gas and oil burner apparatus 12 of the type and arrangement embodying the preferred form of the present invention. In installing apparatus 12 in the furnace the coal burning grates with which the furnace may be originally equipped are removed and a cast or sheet metal cone frustum 14 is placed in the furnace with its base resting on the lugs or rings 16 ordinarily used to support the grate. The cone 14 is centrally apertured to permit the flame issuing from an oil atomizing nozzle 18 to project into the lower part of the furnace without coming into contact with the surface of a solid. Apparatus 12 is mounted in the lower portion of the furnace at one end of a flue 20 which extends into the ashpit 22 of the furnace 10 through the doorway, ordinarily used for removing ashes.

20 The burner apparatus 12 comprises an annular gas burner 24, preferably cast as an integral part of the cone 14, and the oil atomizing nozzle 18, mounted centrally of the gas burner and in a horizontal plane vertically spaced a substantial distance below the plane of the gas burner. The gas burner 24 includes a large number of individual burner tips 26 extending in a ring around its inner edge with their bores directed horizontally and radially 30 toward the central aperture of the burner, so that flames issuing from tips 26 lie in a position to strike the edge of and be drawn at right angles into a jet of atomized oil issuing from the centrally positioned oil nozzle 18. The cone 14 entirely surrounds and extends upwardly a short distance above the level of the burner tips 26. Resting on brackets 28 on the upper edge of cone 14 is a spider 30 supporting a central plate or button 32, preferably made of cast iron and centrally positioned in the furnace so as to contact with and spread oil flame to promote the thorough mingling of the oil flame from nozzle 18 with the gas flame from burner 24.

45 In accordance with the present invention an ideal apparatus arrangement for burning heavy fuel oil is provided by burning gas within a refractory cone to maintain a radiating surface which will readily ignite and vaporize even the heaviest grades of fuel oil. The burner is preferably so operated that at the time oil is introduced into the furnace through the nozzle 18, the gas from burner 24 will be burning at its maximum. Therefore the oil is introduced into a heated chamber and into a burning gas flame, thus insuring its complete combustion. The means for supplying gas and air to burner 24 form no part of the present invention and accordingly are illustrated only diagrammatically in the drawings.

55 A pipe 34 is shown, preferably connected to a gas supply which may be the ordinary city gas. A pipe 36 is taken off from pipe 34 and leads through the flue 20 to a pilot burner 38 adjacent the gas burner 24. Pipe 34 extends to a nozzle 40 arranged to deliver into an air and gas mixing conduit 42, supported in flue 20. The conduit 42 is equipped with air openings 44 at its outer end around the exterior of gas nozzle 40. The gas flowing through nozzle 40 draws proportioned amounts of primary air in around the edges of conduit 42 through passages 44 and the air and gas after mixing in conduit 42 pass into the burner 24. In order that the flame of the gas burner may be regulated as desired, a cap or shutter 46 is movably mounted on a threaded section of the nozzle 40. When moved up against the end of conduit 42 this shutter closes the air passages 44 and shuts off the flow of air into the mixing chamber. Therefore by screwing the cap 46 back and forth on nozzle 40 the flow of air to the burner 24 may be regulated as desired and the cap 46 may be so adjusted with respect to the amount of opening of a valve 48 in gas supply line 34 that any desired percentage mixture of gas and air is admitted to conduit 42 and burner 24. Sufficient secondary air for burning the gas, in case no oil is entering the furnace, will leak in through small openings around the base of the furnace and flue 20, and when oil is being supplied to the furnace additional air will be admitted in a manner hereinafter described. If the burner apparatus is a part of a house heating system the hand valve 48 on the gas line may be preferably replaced by a snap valve of some sort, together with automatic means for operating the valve in accordance with the call for heat registered by a thermostat in some part of the house (not shown).

60 The means for supplying oil to the nozzle 18 and the means for starting and stopping the flow of oil form no part of the present invention and accordingly are merely indicated diagrammatically in the drawing. Oil from a storage tank or other source of supply is preferably raised by pump suction to an oil pump 50 through a pipe 52 and is forced by the pump to nozzle 18 through a pipe 54. Any excess oil handled by the pump and not needed at the burner is by-passed to a pipe 55 and returned to storage. The oil pump 50 illustrated in the drawing is of the valveless or oscillating rotor type. As indicated in the drawings the pump 50 is mounted in alignment with the drive shaft of an electric motor 56 which is energized through a circuit 58. Intermediate oil pump 50 and motor 56 is a pump 60 furnishing air under pressure for atomizing oil delivered by pump 50 at the nozzle 18. The casing of air pump 60 is fixed to the casing of motor 56 and oil pump 50 has its shaft in alignment with those of the motor and air pump. The motor and pumps 50 and 60 form a unitary structure. Air pump 60 receives air through an inlet 61 and delivers it through a pipe 62, supported in

flue 20, to the atomizing nozzle 18. Though not illustrated thermostatic control switches are preferably employed in the circuit of motor 56 for the purpose of automatically starting and stopping the oil pump 50 and blower 60 in accordance with the heat requirements on the furnace 10. Likewise the pilot 38 is equipped with a coil 64 of a fluid-filled thermostat which will operate, upon the extinction 10 of the flame of the pilot, preferably on a fluid motor controlled switch opening the circuit to motor 50 and also on a snap valve or other device cutting off the supply of gas to burner 24. A similar device 66 positioned on 15 the top of the furnace may be employed to interrupt the circuit of motor 56 and thus shut down the motor and oil pump 50 whenever the temperature of the furnace or the pressure on the boiler exceeds certain desired 20 limits. These various automatic safety devices form no part of the present invention and accordingly have not been fully illustrated and will not be more completely described in connection with the present case.

25 As already indicated primary air for atomizing and burning the oil is supplied by pump 60 through pipe 62 to the atomizing nozzle 18. A relief valve 68 near the head of pipe 62 affords the means both for proportioning 30 the amount of air to oil supplied to nozzle 18 and also for regulating the pressure built up in line 62 and the resultant velocity with which the atomized oil-air mixture issues into the furnace from the tip of nozzle 18. For 35 the purpose of supplying additional secondary air to burner apparatus 12 when oil as well as gas is being burned an air inlet aperture 70 is provided in flue 20, aperture 70 being closed by a damper 72 except when oil 40 is being burned. Damper 72 is hinged at 74 to the inside of the bottom surface of flue 20, so that the damper remains normally closed by its own weight. In order to open damper 72 when needed link 76 is connected to the 45 unhinged part of the damper. At its opposite end link 76 is connected to a flexible operating diaphragm 78. Diaphragm 78 is rigidly held in place by the two sections of casing 80 so as to form a tight closure for a chamber 82 in the lower portion of the casing. A 50 pipe 84 connects the interior of primary air supply line 62 with the interior of chamber 82 beneath diaphragm 78. With this arrangement the same air pressure is maintained in 55 chamber 82 that exists in pipe 62. Therefore when the air pump 60 is put into operation the diaphragm 78 will be automatically raised and the damper 72 will be opened to admit secondary air into flue 20.

60 As a result of a large number of tests made with the present burner apparatus, using many classes of oil fields injected into a furnace at the relatively low atomizing air pressure, it has been determined that a condition 65 of substantially noiseless combustion with a

correspondingly high degree of combustion efficiency can be maintained in the furnace when the gas burner 24 is elevated a distance approximating 4" above the tip of oil nozzle 18. In other words it has been found that by 70 adjusting the volume of air passed by blower 60 to oil burner 18 by means of valve 68 in accordance with the type of oil fuel being burned the same relative setting of the gas burner and oil nozzle may be used when burning 75 a wide variety of oils in the furnace without producing any undesirable amount of combustion noise. Thus the valve 68 can be adjusted to change the proportions of air and oil and to vary the velocity of the oil-air mixture issuing from the tip of nozzle 18 to maintain 80 the point of ignition of the oil-air mixture substantially stationary at approximately the desired point at which the velocity of the jet issuing from the nozzle has attained 85 a value equal to the rate of flame propagation of the various air and oil mixtures supplied.

In order to provide for different fuel conditions, means are provided for securing a positive adjustment of the distance separating the tip of nozzle 18 from the plane of burner tips 90. The device illustrated in the drawing consists essentially of a small jack screw arrangement 86 which is shown positioned under the base of nozzle 18. By rotating a worm 88 a rotary movement may be imparted to a pinion 90. The bore of pinion 90 is threaded so that by its rotation it raises or lowers a threaded plunger 92. The head of plunger 92 is positioned to carry the weight of nozzle 18 and by the movement of the plunger it is possible to raise or lower the nozzle through a short distance which, though limited by the angle through which it is safe to swing the pipes 62, 54 and 84, is still sufficient in conjunction with the alternate adjustment afforded by valve 68 to give a wide range of adjustment to the burner apparatus and thus insure noiseless combustion while burning a wide variety of fuel oils. In order to hold the nozzle 18 in a central position in the furnace brackets 94, attached to the base of cone 14, extend downwardly and form with their ends a sleeve journal 95 permitting vertical but not horizontal movement of the nozzle.

The details of construction of atomizing nozzle 18 are illustrated in Fig. 2. Oil or other liquid fuel enters the lower portion of the nozzle casing from pipe 54 through a chamber 96, the top of which is formed into a cap 98. The air for atomizing the oil enters a chamber 100, into which is threaded the pipe 62 leading from air pump 60. From chamber 100 the air passes upwardly through a nipple 102 into an annular opening 104 surrounding a nozzle 106. A pipe 108 is threaded in cap 98 and runs centrally through chamber 100 and nipple 102, to conduct oil into the bore of burner nozzle 106. A protecting cap 110 may if desired be screwed onto threads on the 120

casing of nozzle 18. The upper end of nipple 102 tapers at an angle toward an aperture 112 in nozzle 106, the inner tip of the nipple being spaced from the nozzle so that air may pass up around the outside of the nozzle through an annular aperture 114. Oil is delivered through the pipe 108 and the interior bore of nozzle 106 to the aperture 112 so that air and oil are immediately and thoroughly commingled as they issue from the apertures 112 and 114 respectively.

The operation of the apparatus according to the present invention may be briefly summarized as follows: During periods of normal temperature only the pilot burner 38 is left burning. As the temperature begins to fall the gas valve 48 is opened and cap 46 at the head of conduit 42 is adjusted to admit suitable proportions of gas and air to burner 24. When the maximum supply of gas has been reached the electric circuit of motor 56 is closed and the oil pump 50 and air pump 60 will be simultaneously set in operation to supply oil and air under pressure to nozzle 18. Before the oil pump starts up the cone 14 will have become highly heated by reason of the combustion of gas issuing from the tips of burner 24, so that when the oil is introduced into the furnace from nozzle 18 it will be atomized into the gas flame from burner 24 and into the highly heated chamber formed by cone 14. When the oil pump is started by motor 56 the damper 72 in flue 20 is gradually opened as the air pressure in pipe 62 builds up. This furnishes the secondary air for the oil and gas flame supplied by burner apparatus 16. The oil and gas continue to burn in the furnace until the heat supplied by the boiler is sufficient to raise the temperature in the house to normal, at which time the circuit to the motor 56 will be broken, preferably automatically, and the motor, oil pump and blower will stop. If the temperature continues to rise the supply of gas to burner 24 can be cut off by closing valve 48.

As previously indicated the hand valve 48 illustrated in the drawings may be replaced by a snap valve of some sort with automatic means for controlling the operation of such valve and the supply of gas to burner 24 in accordance with the call for heat registered by a thermostat.

As previously pointed out prior designs of oil and gas-and-oil burning domestic furnaces are so arranged that the pilot flame or other source of ignition is applied to the atomized oil-air mixture at the instant it enters the combustion chamber from the atomizing nozzle. Consequently in operating these burners an unstable condition of combustion is commonly present at the source of ignition and the oil flame which is produced continually bucks and flickers and generates a considerable amount of roaring noise. According to the present design an elevated source

of ignition is used, spaced at exactly the proper distance from the tip of the oil burner so that the velocity of the atomized oil-air mixture is substantially equal to the rate of flame propagation of the mixture at the instant combustion begins. At this point the cross-sectional area of the air-oil jet is many times larger than the area at the base of the jet. Consequently the mixture can be much more readily ignited and combustion will maintain itself at this point without any appreciable amount of bucking or flickering. By employing a gas burner which entirely surrounds the jet of oil and air issuing from the oil burner, the gas flame thrown out from the tips of the gas burner spreads in a substantially horizontal sheet over the entire cross-section of the jet of combustible oil and air mixture issuing from the atomizing nozzle, igniting the mixture throughout the entire cross-section of the jet rather than at a few points in the periphery, as is now the common practice. In other words the ignition of the air-oil jet according to the present invention is effected uniformly throughout its entire cross-section at an elevation where the mixture is prepared to maintain its combustion without any flickering back and forth, producing practically noiseless combustion with a smooth and most desirable character of flame. Moreover, because combustion takes place in a smooth and effective manner the highest degree of efficiency in the combustion of the oil fuel is obtained with a minimum amount of excess air.

Another advantage of using the elevated gas burner is that the atomized mixture is not exposed to the heat of the gas flame until the oil has reached a fine state of atomization and has spread over a relatively large cross section. Intimately exposing the finely atomized oil to the heat of the gas fire at this point gives the burning gas a better opportunity to further break up the oil spray and to completely vaporize the atomized oil, thereby producing efficient combustion without any possibility of carbon formation. In other words by igniting the atomized mixtures at the critical point at which the velocity of the jet entering the furnace is substantially equal to the rate of flame propagation of the mixture, the heat from the source of ignition is most effective in gasifying the combustible air-oil mixture. As previously indicated it is possible to adjust the present apparatus to give efficient and noiseless combustion when burning widely varying grades of oil, and the burner apparatus is so constructed that the atomized air-oil mixture entering the furnace is completely ignited and vaporized without at any time coming into contact with a solid surface, so that there is no deposition of carbon or surface combustion such as usually occurs with the common type of oil burner apparatus.

It is not intended by the foregoing description to limit the invention to the use of air as an atomizing agent for the oil or other liquid fuel, since obviously steam or other suitable atomizing agent for the liquid fuel may be employed without departing from the principle underlying the invention.

The invention having been thus described what is claimed as new is:

- 10 1. The method of burning liquid fuel which comprises jetting an atomized mixture of the fuel and air into a combustion chamber, and vaporizing and igniting the mixture substantially at the point where the velocity of the jet equals the rate of flame propagation of the mixture.
- 20 2. The method of burning fuel oils which comprises injecting an atomized mixture of the oil and an atomizing agent into the combustion chamber of a furnace and throwing a sheet of gas flame transversely across the jet at a point at which the velocity of the jet substantially equals the rate of flame propagation of the mixture.
- 30 3. The method of burning liquid fuels which comprises atomizing a jet of the fuel with air under pressure, throwing a sheet of flame transversely across the path of the jet to ignite it at the point where the velocity of the jet substantially equals the rate of flame propagation of the atomized mixture, and adjusting the ratio of air to fuel in the mixture to maintain substantially uniform and quiet combustion.
- 40 4. The method of burning liquid fuels which comprises atomizing a jet of the fuel with air under pressure, throwing a sheet of flame transversely across the path of the jet to ignite it at the point where the velocity of the jet substantially equals the rate of flame propagation of the atomized mixture, and adjusting the space separating the base of the jet from the point of ignition in accordance with the type of fuel being supplied to maintain substantially uniform and quiet combustion.
- 50 5. The method of burning liquid fuels which comprises injecting a jet of the fuel into a combustion chamber, admixing air with said fuel in amounts sufficient to support its combustion, and igniting the mixture substantially at the point where the velocity of the jet equals the rate of flame propagation of the mixture.

55 In testimony whereof I affix my signature.
ALBERT L. KLEES.
